UNITED STATES PATENT OFFICE.

FREDERICK C. LANGENBERG, OF WATERTOWN, MASSACHUSETTS, ASSIGNOR OF ONE-HALF TO TRACY C. DICKSON, OF WATERTOWN, MASSACHUSETTS.

METHOD OF MAKING HOLLOW METALLIC ARTICLES.

Application filed December 11, 1925. Serial No. 74,818.

In my prior Patents No. 1,552,848, dated September 8, 1925 and No. 1,553,824, dated September 15, 1925, I have described methods and apparatus for making metallic articles by subjecting them to an internal fluid pressure which expands the article to a point beyond the elastic limit of the material employed, the expansion taking place within a container which limits the extent of expansion possible. In the apparatus described in said Patent No. 1,553,824 the pressure is applied to the fluid by means of a separate apparatus, as for instance, the intensifier shown in an application for Letters Patent of the United States filed by John C. Solberg, June 12, 1925, Ser. No. 36,755, and is transmitted to the interior of the hollow article by a suitable conduit. It is frequently desirable to make hollow metallic articles by the method described in my said prior patents without going to the expense of making an intensifier for the purpose, or when one is not available. An intensifier is an elaborate and expensive piece of apparatus. Under other circumstances it may be desired to make hollow metallic articles, the elastic limit of which is higher than can be produced by the capacity of the intensifier, thus, for instance, if the intensifier has a capacity of 100,000 pounds, that is, can produce a pressure on the interior of the hollow article of 100,000 pounds to the square inch, it cannot produce an article which will have an elastic strength caused by expanding the article under pressures much greater than 100,000 pounds to the square inch.

My present invention provides a method by which hollow metallic articles which have been expanded beyond the elastic limit of the material of which they are composed can be made without the use of an exterior intensifier; also, articles having an elastic limit higher than can be produced by the capacity of a given intensifier. Speaking generally my present invention consists in filling the bore of the cylinder which is to be expanded with a suitable liquid, then subjecting the liquid to pressure by a ram which fits the entrance portion of the bore and which expands the cylinder to the required amount, and then drilling out or otherwise removing the metal at the entrance of the bore so that the bore will be of uniform bore throughout. It will be seen that the procedure makes it entirely unnecessary to employ any external source of

fluid pressure such as an intensifier. Another feature of the invention consists in placing in the bore a core of relatively incompressible material such as steel, which reduces the amount of liquid which the bore contains and therefore shortens the stroke of the ram which is necessary to produce a given expansion. In practice, a core which practically fits the bore is employed so that the stroke of the ram is thereby conveniently reduced even to a fraction of an inch.

It will be seen that my invention can be conveniently employed in the manufacture of cylinders for hydraulic presses and that by supplying a new packing for the ram which will fit the final size of the cylinder bore, the press cylinder can be made by the use of the ram which is to be employed in the cylinder and without the manufacture of any special appliances.

The method embodied in my invention is also particularly applicable to the manufacture of open ended cylinders, the material of which is intended to have an extremely high elastic limit.

The invention will be fully understood from the following description when taken in connection with the accompanying drawings and the novel features thereof will be pointed out and clearly defined in the claims at the close of this specification.

In the drawings:

Fig. 1 shows the cylinder from which the final article is to be produced in place in a restraining jacket.

Fig. 2 shows the bore of the cylinder partly filled with liquid and with a solid core and a ram introduced.

Fig. 3 shows the ram moved inwardly and the cylinder expanded until the proper amount of distention is obtained.

Fig. 4 shows the cylinder being rebored.

Fig. 5 shows the cylinder in its final form with the unexpanded portions at the top and bottom cut off.

Referring to the drawings:

In practicing my novel method, I prefer to take a cylinder with one end solid. This cylinder indicated at C may be constructed of a single piece of metal or may be built up of a series of concentric members as circumstances may require. The cylinder is then placed in a suitable restraining jacket B, the interior bore of which is larger than the exterior diameter of the cylinder to be produced.

therein. The amount of difference between the diameter of the cylinder and the bore of the container will depend upon the amount of expansion which it is desired to give to the cylinder. Next, (see Fig. 2), a core M of steel or other relatively non-compressible material is placed in the bore of the cylinder axially concentric therewith and the remaining space is filled to the desired level with a suitable fluid, as for instance, oil N. In practice I make the core M nearly of the size of the bore and have very little space for the expanding fluid N. A ram D provided with a suitable packing E is then fitted to the bore. A suitable packing for the purpose is disclosed in the application of John C. Solberg Serial No. 36,754, filed June 12, 1925.

The entire assembly is then placed under a suitable press having a press member P and a platen L, and the ram D is then forced downward or the cylinder upward until the desired amount of distention is produced. The expansion is limited by the interior of the jacket B. The distention is shown at F in exaggerated manner in Fig. 3.

The ram is then removed, the core is taken out, and the cylinder taken out of the jacket. Next, I enlarge the bore so that it is of uniform diameter throughout its entire length, this being done by removing the surplus metal. A convenient method of doing this is to drill, or bore or ream out the interior. As shown in Fig. 4, a drill G is employed.

It will be seen that by this process the ends of the cylinder are not subjected to the expanding treatment and therefore are of lower elastic limit than the portion of the cylinder walls adjacent the part of the bore which has been expanded, accordingly, if it is desired to produce an article having walls of a uniform elastic limit or to have an open end-

ed cylinder, I cut off the top and the bottom portions of the cylinder as indicated at H and I in Fig. 5.

In some cases, it is desirable to make the cylinder with the closed end and, in this case, the corresponding end of the cylinder is not removed. In other cases the cylinder is intended for use with a piston or ram and under these conditions the ram or piston which is to be used with the completed cylinder can itself be employed in the expansion of the cylinder, it being only necessary to change the packing on the ram to correspond with the increased diameter due to the expansion of the cylinder.

What I claim is:

1. The method of producing a cylinder of material having a high elastic limit which consists in forming a cylindrical cavity therein, filling a portion of the cavity with fluid, subjecting the fluid to pressure by a ram fitting the entrance portion of the cavity thereby expanding the portion of the cylinder surrounding the cavity a predetermined amount and then rendering the bore uniform throughout by removing the surplus metal.

2. The method of producing a cylinder of material having a high elastic limit which consists in forming a cylindrical cavity therein, filling a portion of the cavity with fluid, subjecting the fluid to pressure by a ram fitting the entrance portion of the cavity thereby expanding the portion of the cylinder surrounding the cavity a predetermined amount, then rendering the bore uniform by removing the surplus metal, and then cutting off the ends of the cylinder.

In testimony whereof I affix my signature.

FREDERICK C. LANGENBERG.
